BURIAL VAULT

Edwin F. Nickol, Versailles, Ohio, assignor to
 Edwin F. Nickol, Inc., Versailles, Ohio, a corporation of Ohio

Application September 16, 1935, Serial No. 40,835

9 Claims. (Cl. 72—7)

This invention relates to a burial vault of that type for embedding in the ground and to align with the surface of the latter and has for its object to provide, in a manner as hereinafter set forth, a vault of the class referred to, which, when employed in casket enclosing position will be perfectly dry and moisture tight.

A further object of the invention is to provide, in a manner as hereinafter set forth, a vault of the class referred to including a body section and a lid section and with the said sections having coacting inherent parts to provide air, moisture and water seals when the vault is employed for burial purposes.

15 A further object of the invention is to provide, in a manner as hereinafter set forth, a vault of the type referred to including a body section, a lid section, a head section in the form of a slab anchored upon and coacting with the latter to provide a dead air chamber and upstanding combined anchoring and sealing means between the body section and lid section and with such means being substantially of zig-zag form having its upper and lower end portions preferably of uniform thickness and its intermediate portion gradually decreasing in thickness from the lower to its upper end. The said means not only permanently securing the body and lid sections together, but further acting to prevent the entrance 30 of moisture, water and air into the casket receiving chamber of the vault.

Further objects of the invention are to provide, in a manner as hereinafter set forth, a vault of the class referred to which is comparatively simple in its construction and arrangement, strong, durable, compact, readily assembled, thoroughly efficient in its use, and comparatively inexpensive to manufacture.

With the foregoing and other objects in view, 40 the invention consists of the novel construction, combination and arrangement of parts as will be more specifically described and are as illustrated in the accompanying drawings wherein is shown embodiments of the invention, but it is to be understood that changes, variations and modifications may be resorted to which fall within the scope of the invention as claimed.

In the drawings:

Figure 1 is a perspective view of the vault, 50 Figure 2 is a cross sectional view of the vault as embedded in and flush with the surface of the ground,

Figure 3 is a longitudinal sectional view of the vault,

55 Figure 4 is a perspective view of the form of

coupler element used for detachably connecting to the lid section lowering means therefor, and

Figure 5 is a fragmentary view in vertical section of a modified form of vault.

With reference to Figures 1, 2, and 3, the vault 5 includes an open top body section, a flanged lid section and a flat head slab section indicated generally at 6, 7 and 8 respectively. The body section provides a chamber 9 for receiving the casket 10.

The section 6 is of rectangular contour and includes a bottom 11, a pair of side walls 12, 13 and a pair of end walls 14, 15. The end walls are disposed at opposite outward inclinations with respect to each other. The side walls are disposed at opposite outward inclinations with respect to each other. The section 6 is formed of a moided body of concrete having embedded therein a rectangular reticulated metallic reinforcement 16 formed of a bottom and upstanding 15 side and end parts. The section 6 has also embedded in the bottom and side and end walls spaced parallel metallic reinforcing bars 17 arranged outwardly of and abutting the bottom and side and end parts of the reinforcement 16. 25

The outer faces of each of the walls of section 6 is formed with a lateral rib 18 having a flat upper edge 19. The upper portion 20 of each rib is of uniform width. The lower portion 21 of each rib gradually decreases in width from 30 its point of mergence with portion 20 to its lower end and is of greater height than the portion 20. The ribs 18 on the side walls extend lengthwise of and are of the same length as that of such walls. The ribs 18 on the end walls extend transversely of and are of a length corresponding to the width of such walls. The ends of the ribs on the side walls merge into the ends of the ribs on the end walls. The flat upper edges 19 of the ribs are interposed between the horizontal me- 40 dian of the section 6 and its upper end.

The lid section 7 is of rectangular contour and is employed for closing the open top of section 6. The lower end of section 7 is of greater length and width than that of the top of section 6. 45 The section 7 is formed with an elongated rectangular cavity 21^a opening at its upper end. The side walls and the end walls of the cavity are oppositely outwardly inclined. The section 7 is formed of a rectangular lower portion 22, 50 a frusto-tapered intermediate portion 23 and a rectangular upper portion 24. The portion 23 is of greater height than portions 22, 24. The portion 24 is of greater length and width than portion 22. The section 7 includes a vertically dis- 55

posed depending rectangular endless flange 25 which is integral with the lower face of and has its outer side face flush with the edges of portion 24.

5 The lid section 7 is formed of a molded body of concrete having embedded therein upstanding reticulated metallic reinforcements 26 in its sides and ends and in the sides and ends of the flange. The section 7 has also embedded in portion 22
10 a horizontally disposed reticulated metallic reinforcement 27, and below the latter with spaced parallel metallic reinforcing bars 28. Embedded in section 7 outwardly adjacent the reinforcements 26 are spaced parallel reinforcing bars 29.
15 When the lid section 7 is arranged relative to the body section 6, the flange 25 opposes in spaced relation a portion of the outer face of section 6 above the ribs 18. Embedded in and extending outwardly from each of the side stretches of the
20 flange 25 are spaced couplers 30 each including a pair of threaded stems 31 carrying on their outer ends nuts 32 which abut the outer face of the said stretch. The nuts 32 are employed for detachably connecting a lid lowering device, not shown to the lid section 7. The latter has its sides formed with drain channels 33 for the cavity 21^a. The channels 33 extend downwardly at an inclination from their inner to their outer ends and are arranged in the intermediate and lower
25 portions 23, 24 of section 7. When flange 25 is arranged in encompassing relation with respect to that portion of the outer face of section 6 above the top edges of the ribs 18 it provides a vertical space 34 which gradually decreases in width from its lower to its upper end. When the lid section 7 is arranged in closure position with respect to the open top of section 6 the lower portion 22 of section 7 seats upon the top edge of section 6 and the bottom edge of flange 25 is spaced from
30 the top edges of the ribs. When the sections 6, 7 are arranged in such position an air tight seal is formed. If water should enter between the flange and ribs the level thereof in space 34 would be near the lower end of the latter and provide a
35 seal.

The head section 8 is mounted on section 7 and is in the form of a slab 35 of rectangular contour corresponding in width and length to that of portion 24 of section 7 which it is supported by.
40 The slab 35 is formed of a material, such as marble or granite which will not deteriorate on account of atmosphere conditions. The slab may have its upper face provided with any suitable inscription. The section 8 is anchored to section 50
45 7 by any suitable cementitious material, indicated at 36 arranged on the upper edge parts of the portion 24 of section 7. The section 8 closes the top of and forms in connection with the cavity 21^a a dead air chamber for the reception of any moisture from the interior of the section 6, and also for receiving water which due to some cause may enter the cavity 21 through between the sections 7, 8. The sections 6, 7 and 8 are to be embedded in the ground.
55

The sections 7 and 8 coact to provide a lid structure for closing and sealing the section 6. When the lid structure is mounted in closure position relative to section 6, the upper end thereof is to be substantially flush with the level of the ground.
60

With reference to Figure 5 a modification of the vault is shown. This modified form is the same in all particulars as the form shown in Figures 1, 2, 3 with this exception, that there is
65

arranged upon the top edges of body section 37 a portion of a combined anchoring and sealing medium 38 of any suitable character, such by way of example asphaltum. The remaining portion of the sealing medium is interposed between the flange 39 of lid section 40 and the body section 37 and between the top edge 42 of the ribs 43 and the bottom edge of flange 39. The combined sealing and anchoring medium is of zig-zag form having upper, lower and intermediate 10 stretches 44, 45, and 46 respectively. The stretches 44, 46 are of uniform thickness. The stretch 45 gradually decreases in thickness from its point of mergence and stretch 45 to its point of mergence with stretch 44. The stretch 46 completely fills the tapered space 47 formed between the flange 39 and body section 41. The medium 38 not only anchors sections 40, 41 together but further constitutes an air, moisture and water tight seal.
20

What I claim is:

1. In a burial vault an open top body section having oppositely outwardly inclined side walls and oppositely outwardly inclined end walls, said walls being formed on their outer faces, below 25 their upper ends with laterally extending ribs merging into each other, and a lid section for closing said body section, said lid section being formed with a depending upstanding endless flange having its inner face encompassing and 30 opposing in spaced relation the outer face of the body section above said ribs, that part of the lower face of said lid section bordering the upper end of said inner face of said flange seated directly upon and throughout the top edges of the 35 walls of said body section, and the said inner face of said flange inclining from its lower end to its upper end throughout in a direction towards the walls of said body section.

2. In a burial vault an open top body section 40 having oppositely outwardly inclined side walls and oppositely outwardly inclined end walls, said walls being formed on their outer faces, below 45 their upper ends with laterally extending ribs merging into each other, and a lid section for closing said body section, said lid section being formed with a depending upstanding endless flange having its inner face encompassing and 50 opposing in spaced relation the outer face of the body section above said ribs, that part of the lower face of said lid section bordering the upper end of the said inner face of said flange seated directly upon and throughout the stop edges of the walls of said body section, the said inner face of said flange inclining from its lower to its 55 upper end throughout in a direction towards the walls of the said body section, said ribs having flat top edges, and said flange having its bottom edge opposing in spaced relation the top edges of said ribs.
60

3. In a burial vault an open top body section having oppositely outwardly inclined side walls and oppositely outwardly inclined end walls, said walls being formed on their outer faces, below 65 their upper ends with laterally extending ribs merging into each other, and a lid section for closing said body section, said lid section being formed with a depending upstanding endless flange having its inner face encompassing and 70 opposing in spaced relation the outer face of the body section above said ribs, that part of the lower face of said lid bordering the upper end of the inner face of said flange seated directly upon and throughout the top edges of the walls of said body section, the inner face of said flange inclin- 75

ing from its lower to its upper end throughout in a direction towards the walls of said body section and coacting with the outer face of the body section above the ribs to form a tapered space 5 therebetween.

4. In a burial vault an open top body section having oppositely outwardly inclined side walls and oppositely outwardly inclined end walls, said walls being formed on their outer faces, below 10 their upper ends with laterally extending ribs merging into each other, and a lid section for closing said body section seated directly upon the upper edge of and, said lid section being formed with a depending upstanding endless 15 flange having its inner face encompassing and opposing in spaced relation the outer face of the body section above said ribs, said lid section including a lower portion, an intermediate portion and an upper portion, said lower portion being 20 of greater length and width than that of said body section and said upper portion, said intermediate portion being of frustotapered contour, said body and lid sections for embedding in the ground, and a head section in the form of a slab 25 corresponding in width and length to that of said upper portion and anchored to the latter, said head section for embedding in the ground with its upper face exposed to the atmosphere and being formed of a material different from that of said 30 sections and possessing a characteristic to prevent the deterioration thereof by atmospheric conditions.

5. In a burial vault an open top body section having oppositely outwardly inclined side walls 35 and oppositely outwardly inclined end walls, said walls being formed on their outer faces, below their upper ends with laterally extending ribs merging into each other, and a lid section seated directly upon the top edge of and for closing said 40 body section, said lid section being formed with a depending upstanding endless flange having its inner face encompassing and opposing in spaced relation the outer face of the body section above said ribs, said lid section including a lower portion, an intermediate portion and an upper portion, said lower portion being of greater length and width than that of said body section and said upper portion, said intermediate portion being of frustotapered contour, said body and lid 45 sections for embedding in the ground, and a head section in the form of a slab corresponding in width and length to that of said upper portion and anchored to the latter, said head section for embedding in the ground with its upper face exposed to the atmosphere and being formed of a material different from that of said sections and possessing a characteristic to prevent the deterioration thereof by the atmosphere, 50 said lid section being formed in its upper and intermediate portions with a cavity opening at the top thereof, said head section closing the top of the cavity and forming in connection therewith a dead air chamber for absorbing any moisture from the body section, and said lid section being formed with drainage channels for said chamber arranged in said intermediate and lower portions thereof.

6. In a burial vault an open top body section 70 having oppositely outwardly inclined side walls and oppositely outwardly inclined end walls, said walls being formed in their outer faces, below their upper ends with laterally extending ribs merging into each other, and a lid section having the marginal portions of its lower face seated directly

upon and throughout the top edge of and for closing said body section, said lid section being formed at its bottom with a depending upstanding endless flange having its inner face encompassing and opposing in spaced relation the outer face of the body section above said ribs, said ribs having flat top edges, and said flanges having its bottom edge opposing in spaced relation the top edges of said ribs, the inner face of said flange coacting with the outer face of the body section 10 above the ribs to form a tapered space therebetween, and a sealing means having an upper portion interposed between the said sections, a tapered intermediate portion arranged between the body section and flange and a lower portion arranged between the bottom edge of the flange and the top edges of said ribs. 15

7. In a burial vault an open top rectangular body section for embedding in the ground having side walls and end walls and lateral ribs on the 20 outer faces of said walls above the bottoms of the walls, disposed lengthwise of the side walls, transversely of the end walls and merging into each other, and a rectangular lid structure having its lower face seated directly upon and throughout the upper edges of and for closing the said open top, said lid section having its lower face of greater length and width than that of said section, said structure being formed at its bottom with a depending endless rectangular flange opposing in 25 spaced relation the outer faces of said walls above said ribs, said flange coacting with the outer faces of said walls to provide a tapered space between said faces and flange, said structure adapted to be embedded in the ground and including a top 30 part in the form of a rectangular slab for exposure to the atmosphere, said slab being formed of a material different from that of the remaining part of the lid structure and possessing a 35 characteristic to prevent the deterioration thereof by atmospheric conditions. 40

8. In a burial vault an open top rectangular body section for embedding in the ground having side walls and end walls and lateral ribs on the 45 outer faces of said walls above the bottoms of the walls, disposed lengthwise of the side walls, transversely of the end walls and merging into each other, and a rectangular lid structure having its bottom seated directly upon the top edges throughout of said walls for closing the said open top and having its bottom of greater length and width than that of said section, said structure being formed at its bottom with a depending endless rectangular flange opposing in spaced 50 relation the outer faces of said walls above said ribs, said flange coacting with the outer faces of said walls to provide a tapered space between said faces and flange, said structure adapted to be embedded in the ground and including a top part in 55 the form of a rectangular slab for exposure to the atmosphere and possessing a characteristic to prevent the deterioration thereof by atmosphere conditions, and said structure below said top part being formed with a dead air chamber for collecting moisture, and said structure being provided with downwardly inclined drainage channels for said chamber. 60

9. In a burial vault, an open top rectangular body section having an endless rib on its outer 70 periphery below its top, a rectangular lid structure including a lower portion of greater length and width than said body section, said lower portion seated directly upon the top edge of said body section and extended laterally from the latter, 75

5 said lower portion being formed with a depending endless flange opposing in spaced relation the outer face of said body section above said rib, said structure including an intermediate portion of less length and width than that of said lower portion and an upper portion corresponding in length and width to the top of said intermediate portion, said structure being formed in said upper and intermediate portions with a cavity, said structure including a top part in the form of a 10 rectangular slab corresponding in width and

length to and secured to said upper portion for closing said cavity and forming, in connection with the cavity, a dead air space, said slab being of material different from that of said lid structure and body section and possessing a characteristic to prevent the deterioration thereof by atmospheric conditions, and said lid structure for embedding in the ground with the slab thereof exposed to the atmosphere. 15

10

EDWIN F. NICKOL.
